UNITED STATES PATENT OFFICE

LOUIS SIMON FRAPPIER AND EWALD BOECKING, OF BROOKLYN, NEW YORK, ASSIGNEES
TO INTERNATIONAL PROJECTOR CORPORATION, OF NEW YORK, N. Y., A CORPORATION
OF DELAWARE

SPROCKET

Original application filed October 27, 1928, Serial No. 315,381. Divided and this application filed September 30, 1930. Serial No. 485,412.

This invention relates to motion picture projection machines, and more particularly to a self-aligning sprocket therefor.

This application is a division of our co-pending application, Serial No. 315,381 filed October 27, 1928, for Self-Aligning Sprocket, which is a division of our co-pending application Serial No. 303,162, filed August 31, 1928, for improvements in projection machine.

An object of the invention is to provide a sprocket capable of feeding a wide film to and from a film magazine.

Another object is to prevent tearing of the film due to minor variations in the line of travel thereof.

Other objects and advantages will be apparent as the nature of the invention is disclosed. These objects are accomplished by providing a feed sprocket with a swivel connection to the power shaft, whereby the axis of said sprocket may be angularly varied to compensate for changes in direction of the film feed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawing forming a part thereof, in which

Fig. 1 is an elevation of a self-aligning sprocket and driving shaft therefor;

Fig. 2 is a sectional view thereof;

Fig. 3 is a front elevation of the resilient driving mechanism; and

Fig. 4 is a section taken on the line 4—4 of Fig. 2 showing the supporting means for the sprocket.

Like reference characters denote like parts in the several figures of the drawing.

In the following description and in the claims parts will be identified by specific names for convenience, but they are intended to be as generic in their application to similar parts as the art will permit.

Referring to the drawing more in detail,

the support for the feed sprocket 10 which is adapted to feed a wide film having edge perforations comprises a rod 25 which is clamped to frame 26 of the machine by means of shoulder 27 and nut 28. Rod 25 is provided with a pair of bearings 29 and 30 on which sleeve 31 is journaled. Sleeve 31 is held against longitudinal movement by nut 32 threaded on shaft 25 and bearing against a shoulder in said sleeve.

A tubular member 35, having its end rounded to form ball 36, is carried on the end of sleeve 31 and secured thereto by means of plug 37 which is threaded interiorly of said sleeve. Member 35 may be secured to said plug 37 by pin 38 (Fig. 4) which passes through aligned apertures in said members. Sprocket 10 is secured to web member 40 by means of screw 41. Said web member is provided with a spherical surface forming a socket 42 which is adapted to contact with ball 36 of member 35. Web member 40 may be secured against rotational movement with respect to ball 36 by means of stud 45 threaded in said ball and cooperating with a keyway 46 in web member 40.

Ball 36 and socket 42 are held in engaging relationship by spring 47 which is secured between washer 48 carried by bolt 49 and flanged member 50 journaled on said bolt and adapted to bear against said web member 40. Bolt 49 is secured in sleeve 31 by means of nut 51 which is threaded interiorly thereof.

Sleeve 31 passes through aperture 60 in a partition 61 forming a part of the frame of the machine, and is provided at that point with threads 62 which are designed to prevent oil from creeping along the surface of said sleeve toward the sprocket and to discharge such oil into the gear chamber formed between partition 61 and frame 26. Shield 63 may be attached to sleeve 31 by any suitable means and is so positioned as to prevent direct passage of oil around said sleeve.

The driving means for sleeve 31 comprises a gear wheel 65 which is loosely journaled about sleeve 31 between shoulder 27 and shoulder 66. Springs 67 are connected between pins 68 carried by said gear wheel 65

and pins 69 carried in said shoulder 66. Suitable slots are provided in gear wheel 65 adjacent pins 69 whereby a slight relative movement is permitted between said gear wheel and sleeve 31.

5 Oil hole 71 is adapted to direct oil upon bearings 29 and 30. Any oil which passes said bearings cannot pass nut 51 and is accordingly returned past bearings 29 and 30 and discharged through oil hole 70.

10 The sprocket is capable of pivoting to a limited extent about the ball and socket connection above described, and is accordingly adapted to equalize the stress on the film which would be caused by a slight change in direction of feeding. The resilient connection between the driving gear and between sleeve 31 prevents the film from being torn due to sudden changes in driving force or sudden variations in tension of the film itself. 15 The oiling mechanism is so constructed that oil is prevented from coming in contact with the sprocket or the film carried thereby. Shield 63 prevents oil from passing directly 20 into the film chamber while threads 62 on sleeve 31 prevents creepage along said sleeve. 25

Although a specific embodiment of the invention has been shown and described for purposes of illustration, it is to be understood that various omissions, substitutions and changes in the forms and details of the device illustrated and in its operation, may be made by those skilled in the art without departing from the scope of the invention, 30 which is not to be limited by the present specific description, but only in accordance with the following claims.

What is claimed is:

1. In combination, a sprocket wheel and a 40 driving shaft therefor, one of said elements having a ball and the other of said elements having a hemispherical socket in driving engagement therewith whereby limited relative angular variation between said elements is 45 permitted and resilient means carried by one of said elements for securing said ball and socket in driving engagement.

2. In combination with a rotating shaft, a 50 tubular member secured thereto having a ball shaped end, a sprocket having a web formed interiorly thereof, said web having a hemispherical surface, resilient means for maintaining said ball shaped end and said hemispherical surface in contact, and means including a pin and slot connection for transmitting a driving force therebetween.

3. A sprocket mounting comprising a 60 rotating shaft having a ball shaped end, a hollow sprocket having a web formed interiorly thereof, said web having a socket engaging said ball shaped end, a rod extending from said shaft axially of said sprocket, and a spring seated on said rod and engaging said web for holding said spherical surface in engagement with said ball shaped end.

4. A sprocket mounting comprising a driving shaft having a ball shaped end, a sprocket having a web formed interiorly thereof and engaging said end to form a ball and socket joint, a shaft mounted co-axially with said driving shaft and carrying a spring, said spring engaging said web and holding said web in engagement with said end, a longitudinal slot formed in said web, and a key mounted in said end and engaging said slot to provide a driving connection and means for varying the tension of said spring for controlling the flexibility of said sprocket. 70 75

5. A sprocket support comprising a hollow driving shaft, a tubular member secured thereto and having a ball shaped end, a hollow sprocket having a web formed interiorly thereof and engaging said end to provide a ball and socket joint, a rod extending through said end and carrying a spring, said spring bearing against said web and holding said ball and socket joint in operative position, a key driving connection between said end and said web, and a member threaded interiorly of said shaft and engaging said rod for locking the same in position. 80 85

6. A sprocket mounting comprising a hollow driving shaft, a member secured to the end of said shaft and carrying a ball shaped end, a hollow sprocket having a web formed interiorly thereof, said web having a socket engaging said ball shaped end, a rod extending from said member axially of said sprocket, and a spring seated on said rod and engaging said web for holding said spherical surface in engagement with said ball shaped end. 90 95 100

7. A sprocket support comprising a hollow driving shaft, a tubular member secured thereto and having a ball shaped end, a hollow sprocket having a web formed interiorly thereof, and engaging said end to provide a ball and socket joint, a plug in said tubular member, a rod threaded into said plug and extending through said end and carrying a spring, said spring bearing against said web and holding said ball and socket joint in operative position, a key driving connection between said end and said web, and a member threaded interiorly of said shaft and engaging said threaded rod for locking the same in position. 105 110 115

In testimony whereof we have hereunto set our hands.

LOUIS SIMON FRAPPIER.
EWALD BOECKING.
